(57) CLAIM

The ornamental design for a desk accessory, as shown and described.

DESCRIPTION

FIG. 1 is a front view of the desk accessory; FIG. 2 is a rear view of the desk accessory; FIG. 3 is a right side view of the desk accessory; FIG. 4 is a left side view of the desk accessory; FIG. 5 is a top view of the desk accessory; FIG. 6 is a bottom view of the desk accessory; FIG. 7 is a perspective view of the desk accessory from the right; FIG. 8 is a perspective view of the desk accessory from the left; and, FIG. 9 is a right side view of the desk accessory attached to a desk.

The broken lines shown in FIG. 9 are for illustrative purposes only to show the environment in which the desk accessory is used, and forms no part of the claimed design.
